[57] CLAIM

The ornamental design for a jewelry pin, as shown and described.

DESCRIPTION

FIG. 1 is a perspective view of a jewelry pin, showing my new design;

FIG. 2 is a left side elevational view of FIG. 1;

FIG. 3 is a right side elevational view of FIG. 1;

FIG. 4 is a top plan view of FIG. 2;

FIG. 5 is a bottom plan view of FIG. 4;

FIG. 6 is an enlarged left side view of FIG. 2; and,

FIG. 7 is an enlarged right side view of FIG. 2.

The broken line showing of a rose bud, in FIG. 1, is for illustrative purposes only and forms no part of the claimed design.
